[57] CLAIM

The ornamental design for a golf ball pouch, as shown
and described.

DESCRIPTION

FIG. 1 is a front perspective view of a golf ball pouch
showing my new design;

FIG. 2 is a rear perspective view thereof;

FIG. 3 is an enlarged top plan view thereof;

FIG. 4 is a front elevational view thereof;

FIG. 5 is a right side elevational view thereof;

FIG. 6 is a rear elevational view thereof;

FIG. 7 is a cross-sectional view taken along line 7—7 of
FIG. 6;

FIG. 8 is a bottom plan view thereof.
